UNITED STATES PATENT OFFICE

ALFRED L. BRANDT, SR., OF BUFFALO, NEW YORK, ASSIGNOR TO FLEXLUME CORPORATION, OF TONAWANDA, NEW YORK, A CORPORATION OF NEW YORK

ELECTROLUMINESCENT TUBE BEACON

Application filed March 25, 1929. Serial No. 349,587.

This invention relates to improvements in electroluminescent or neon tube constructions proposing a construction which is particularly useful as a beacon in airports and the like.

The use of neon or other electroluminescent tubes as beacons is particularly desirable in airports due, among other things, to the fog-penetrating powers of the light emanating from the tubes. In order to increase the amount of the light, it has been proposed to increase the diameter of the tubes. While this may be easily accomplished, it has the objections of necessitating a special transformer to accommodate the increased current requirement and of increasing the number of tube breakdowns due to the heat evolved within the tube as a result of the increased current. Furthermore, with a tube of increased diameter, the brilliancy of light is decreased with in practical current values.

The principal object of this invention is to eliminate the need of tubes of increased diameter together with their attendant objections.

A further object is to secure increased brilliancy of light by a construction involving a neon tube of ordinary or standard diameter and current capacity.

A still further object is to provide a simple sturdy construction which may be readily cleaned.

An embodiment of the invention is illustrated in the accompanying drawings, wherein:

Figure 1 is a plan view of the construction.

Figure 2 is a section along line 2-2 of Fig. 1.

In accordance with my invention, the display portion of an electroluminescent tube 1 is formed with a series of closely spaced convolutions 2. These convolutions may be of any suitable form but preferably are made in the form of a spiral, the spirals preferably being of uniform diameter. While this tube may be of various diameters, a tube of relatively small diameter, as compared with ordinary or standard diameters, is preferred. A tube of this form, when illuminated and viewed from a distance, appears as a single broad band of light having the same effect as

a single tube of a diameter equal to the diameter of the spirals but of considerably greater brilliancy. The breadth of this band of light may be, and preferably is, increased by the provision of one or more mirrors extending 55 adjacent to the tube. In the construction shown, two mirrors 3 and 4 are utilized, these being placed at either side of the tube and supported in any suitable manner.

The spirally formed tube 1 has a pronounced measure of flexibility and, in accordance with the invention, is enclosed within, and supported by, a substantially rigid glass cylinder 5. The opposite ends of the cylinder 5 preferably are joined to the walls of the tube 1 thereby preventing the access of dirt to the spiral portion 2 of the tube while the intermediate portion of the cylinder preferably engages the spiral portion 2 at various points along its length to support the same. 70 Obviously, to clean the tube it is only necessary to clean the outer walls of the cylinder which may be readily accomplished. Furthermore, the cylinder 5 affords the necessary rigidity of the structure notwithstanding the 75 flexibility of the spiral portion 2.

In constructions where the use of the mirrors 3 and 4 is not desired or necessary, the brilliancy of the tube may be increased by providing the rear half of the cylinder 5 with 80 a mirrored coating. While such coating might be placed on the outer surface of the cylinder 5, it preferably would be placed on the inner side of the cylinder where it would be protected against dirt and the elements. 85 Instead of a coating, strictly so-called, a bright plate of metal might be used and secured to either the outer or inner face of the cylinder.

Having described my invention, I claim:

1. A construction of the class described, comprising an electroluminescent tube having a display portion formed with a series of convolutions which are arranged to give the effect of a broad band of light when the tube is illuminated, and a substantially rigid transparent envelope enclosing said display portion and engaging the same to support it at points along its length.

2. A construction of the class described,

comprising an electroluminescent tube having a display portion arranged in the form of a spiral and a substantially rigid sleeve enclosing said spiral portion and engaging the same to support it at points along its length.

5 In testimony whereof I affix my signature.
ALFRED L. BRANDT, SR.
